UNITED STATES PATENT OFFICE.

EDWIN L. ROGNESS, OF KENNETH, MINNESOTA.

RIVETING-TOOL.

1,331,381.

Specification of Letters Patent. Patented Feb. 17, 1920.

Application filed May 19, 1919. Serial No. 298,074.

To all whom it may concern:

Be it known that I, EDWIN L. ROGNESS, a citizen of the United States, residing at Kenneth, in the county of Rock and State 5 of Minnesota, have invented new and useful Improvements in Riveting-Tools, of which the following is a specification.

This invention relates to tools, particularly to tools used in riveting, and has for 10 its object the provision in a single tool, of a device for holding a rivet while it is being started in position, a device for facilitating the driving on of the usual washer, means for cutting off the rivet in the event that it 15 is too long, and means for burring the rivet after the washer is placed thereon.

An important object is the provision of 20 a device of this character constructed fundamentally in plier form, the jaws of the pliers serving as nippers for cutting off an excessively long rivet, and the end of one of the members being provided with a recess 25 for burring or upsetting the rivet and also being provided with a hole permitting the passage of the rivet when a washer is driven thereonto.

A further object is the provision of a 30 tool of this character which will be simple and inexpensive in manufacture, highly efficient in use, durable in service, and which will be extremely handy and a labor saver.

With the above and other objects and advantages in view, the invention consists in the details of construction to be hereinafter 35 more fully described and claimed, and illustrated in the accompanying drawings, in which—

Figure 1 is a side elevation of the tool,

Fig. 2 is an elevation thereof taken at 40 right angles to Fig. 1,

Fig. 3 is an end elevation,

Fig. 4 is a cross-sectional view on the line 4-4 of Fig. 3,

Fig. 5 is a detail cross-sectional view 45 through the rivet holder,

Fig. 6 is a diagrammatic view of the device showing it in position for the insertion of a rivet in a strap or the like,

Fig. 7 is a view of a rivet projecting 50 through a strap and having a washer engaged thereon and having my device engaged thereon in the process of driving down the washer, and

Fig. 8 is a similar view showing the device 55 in use for upsetting the rivet.

Referring more particularly to the draw-

ing, the letter A designates a harness strap or the like, B designates a rivet, and C designates a washer.

In carrying out my invention I provide 60 a pair of members 10 and 11, the former of which is straight and the latter of which is curved and crosses the former. These members are pivotally connected, as shown at 12, and it will be noted that the general 65 construction is that of a pair of pliers. Formed on the end of the straight member 10 adjacent its pivot point 12 is a head 13, at one side of which is formed a blade 14 adapted to coöperate with a blade 15 formed 70 at the pivoted end of the curved member 11. These blades form nippers whereby rivets may be cut.

Pivots secured upon the straight member 10, as shown at 16, is a rivet holder in 75 the nature of a plate 17 normally lying along the member 10 but disposable when in service to extend preferably at right angles thereto. This plate 17 has secured thereon, as shown at 18, a spring plate 19 provided 80 with a slot 20 adapted to receive a rivet and having a projecting end portion 21 whereby the spring plate 19 may be sprung slightly away from the plate 17 to permit the engagement of the head of a rivet between 85 these plates with the shank of the rivet extending through the slot 20.

Formed in the head 13 adjacent one corner thereof is a cylindrical hole 22 adapted to receive the shank of a rivet, as will be 90 hereinafter described, and formed in the head at another corner is a concavity or depression 23 adapted to serve as a die for upsetting and preferably finishing a rivet after a washer has been placed thereon. 95

The use of the device is as follows:—

Assuming that an operator wishes to secure together a couple of straps A, he first grasps the projection 21 of the rivet holder and engages the head of a rivet B between 100 the spring plate 19 and plate 17 with the shank of the rivet extending through the slot 20. At this time it should be stated that it is preferable that the plate 17 be swung upon its pivot 16 to extend at substantially right angles to the member 10 so as to be unobstructed thereby. The rivet being thus held its point is placed upon the superposed straps A and a smart blow is struck upon the plate 17 by a hammer or the 110 like to start the rivet. It is then preferable that the operator so move the device that the

slot 20 in the spring plate 19 will permit the rivet holder to disengage the rivet. The rivet is then driven through the straps A as far as possible. The straps A are then 5 turned over so that the point of the rivet will then extend upwardly and the washer C is placed upon the rivet. The operator then grasps the member 10 and so disposes it that the point of the rivet enters the hole 22 10 in the head 13. By means of a sharp blow upon the upper end of the member 10, the washer C is then driven home. If the shank of the rivet then projects too far beyond the washer, use may be made of the 15 blades 14 and 15 by using the device as a nipper for cutting off the excessive length of the rivet. After the rivet has been properly secured, if it should happen to need it, the device is so positioned that the concavity 20 or depression 23 is disposed over the projecting end of the rivet, whereupon by means of a sharp blow upon the upper end of the handle member 10, the rivet will be properly burred or upset upon the washer. The 25 riveting operation is thus completed.

From the foregoing description and a study of the drawings it will be apparent that I have thus provided a very simple and inexpensive tool by means of which

riveting may be very quickly and easily done 30 in view of the fact that all the tools necessary for the operation are embodied in one simple compact tool ready for use in the different operations.

While I have shown and described the 35 preferred embodiment of my invention, it is of course to be understood that I reserve the right to make such changes in the form, construction, and arrangement of parts as will not depart from the spirit of the invention or the scope of the subjoined claim. 40

Having thus described my invention, I claim:—

A device of the character described comprising a pair of handle members, one 45 formed straight and the other curved and crossed with respect to said straight member, said members being pivotally connected at the point of crossing, rivet holding means associated with said straight member, a 50 head formed on said straight member and provided with a rivet receiving hole and also provided with a shallow depression constituting a die, and said members coöperating to form rivet cutting means.

In testimony whereof I affix my signature. 55

EDWIN L. ROGNESS.
